(57) **CLAIM**

The ornamental design for an automotive spoiler as shown and described.

DESCRIPTION

FIG. 1 is a top, front, left perspective view of an automotive spoiler, in accordance with an embodiment;

FIG. 2 is a bottom, front, left perspective view of the automotive spoiler of FIG. 1;

FIG. 3 is a front view of the automotive spoiler of FIG. 1;

FIG. 4 is a rear view of the automotive spoiler of FIG. 1;

FIG. 5 is a right side view of the automotive spoiler of FIG. 1;

FIG. 6 is a left side view of the automotive spoiler of FIG. 1;

FIG. 7 is a top view of the automotive spoiler of FIG. 1;

FIG. 8 is a bottom view of the automotive spoiler of FIG. 1;

FIG. 9 is a top, front, left perspective view of an automotive spoiler, in accordance with an embodiment;

FIG. 10 is a bottom, front, left perspective view of the automotive spoiler of FIG. 9;

FIG. 11 is a front view of the automotive spoiler of FIG. 9;

FIG. 12 is a rear view of the automotive spoiler of FIG. 9;

FIG. 13 is a right side view of the automotive spoiler of FIG. 9;

FIG. 14 is a left side view of the automotive spoiler of FIG. 9;

FIG. 15 is a top view of the automotive spoiler of FIG. 9; and,

FIG. 16 is a bottom view of the automotive spoiler of FIG. 9.

The ornamental design which is claimed is shown in solid lines in the drawings. The broken lines of equal length dashes in the drawings are for illustrative purposes and form no part of the claimed design. Broken lines formed by unequal length dashes (i.e., dash-dot) define bounds of the claimed design.

1 Claim, 14 Drawing Sheets
